HAIR-WAVING APPARATUS.

1,400,370.

Specification of Letters Patent. Patented Dec. 13, 1921.

Application filed April 16, 1918. Serial No. 228,371.

To all whom it may concern:

Be it known that I, CHARLES NESSLER, a citizen of the United States, residing in New York city, county and State of New York, 5 have invented certain new and useful Improvements in Hair-Waving Apparatus, of which the following is a specification.

The waving of the hair on the head as heretofore accomplished by wetting the hair 10 and then manipulating it with the fingers and applying one at a time separate and independent combs, is, perhaps, the most natural method of waving the hair and it is a desirable method because it is not liable to accidentally injure the hair, nevertheless, 15 the great skill required in performing this method, not only prevents the great majority of women from waving their own hair, but also makes it most difficult to have 20 the work done even by a skilled hair-dresser. In most human hair there is some inherent natural waviness which is developed under a water treatment but is defeated by the use of heated irons or curling pins where 25 dry heat is used. By virtue of my improvements herein set forth, the waving of hair by use of water and combs does not require the skill heretofore demanded by the old 30 practice and the waving is rendered so easy and simple that persons are enabled to wave their own hair on the head, and moreover the individual hairs are caused to be waved with almost complete uniformity and accuracy so 35 that the innumerable hairs fit one in to the other, each being bent or waved substantially alike, thereby insuring the long retention 40 of the wave-form, which may remain for many weeks, especially in hair which has wavy qualities of its own but insufficient to show ordinarily.

My invention provides means by which water-waving can be done by anybody on their own hair or somebody else's hair and which can be used on transformations, wigs 45 and other hair made up artificially. My improvements consist in the various novel arrangements and combinations of the several different parts of the apparatus, all as hereinafter fully set forth and then pointed out in the claims.

I have illustrated types of my invention in the accompanying drawings, wherein;

Figure 1, is a top plan view of my improved device in expanded or open position 55 ready for insertion in the hair to be waved.

Fig. 2, is a perspective view of the device shown in Fig. 1.

Fig. 3, is a top plan view of the device shown as partially collapsed or closed to bring the combs closer together and shift 60 them endwise into their final positions in which the hair is dried to retain the wave.

Fig. 4, is an under side view of the apparatus expanded as shown in Figs. 1 and 2, and inserted in the hair which is shown diagrammatically as straightened prior to moving the combs toward each other. This view is on a reduced scale and the combs are shown as arranged substantially in line with each other in sidewise relation.

Fig. 5, is a similar view to that shown in Fig. 4, but with the combs moved into their final waving positions as shown in Fig. 3, and this view also shows the hair in diagrammatic form and the scale of the view 75 is reduced.

Fig. 6, is a diagrammatic view of a portion of the hair showing how it is finally waved by the use of the apparatus.

Fig. 7, is a side view of a modified form 80 of comb in which the teeth are telescopic. Fig. 8, is a modified form.

Referring to the drawings in which like numerals of reference designate like parts throughout, I employ a set or gang of similar sized hair-combs 1, shown here as five in number though more or less may be used. The points of the teeth of the combs do not lie in the same plane but take the form of an arch so as to conform to the curvature 90 of the head of the subject in order that each tooth may reach the scalp and get a good grip on the hair in which the comb is inserted when waving the hair. The same effect of the arch 2, of the edge of the comb 95 may also be obtained by having the comb-teeth made telescopic as shown in the comb 3, in Fig. 7, wherein the teeth have a tubular base section 4, with an outer solid part 5, sliding therein and provided with a 100 spring 6, for pressing the sliding part outwardly. When this form of comb is pressed against the head the teeth will yield and move inwardly and thus conform to the curvature of the head.

The comb at one end is loosely connected to the adjoining comb by means of a pair of links 7 and 8, which are respectively pivoted at one end to the end comb at 9, and 11, and at the other ends to the adjacent comb 110

at 10, and 12, respectively. A similar pair of links 13, and 14, are pivoted at corresponding ends at 10, and 12, to the second comb while the other ends of said links are 5 pivoted to the adjacent and third comb at 15, and 16, respectively. A similar pair of links 17, and 18, are pivoted at corresponding ends at 15, and 16, to the third comb and their other ends are pivoted at 19, and 20, 10 respectively, to the fourth comb, while similar links 21, and 22, are pivoted at 19, and 20, to the fourth comb at corresponding ends and have their other ends pivoted at 23, and 24, to the fifth and last comb of the 15 set. These links between adjacent combs act like those of a parallel-ruler and maintain the combs in parallelism while they permit the combs to be moved relatively toward each other in sidewise relation and also 20 shifted relatively endwise. The adjacent pairs of links are flexed or bent in opposite directions when the combs are applied in the waving process, as shown in Figs. 3, and 5, making a zig-zag disposition of them and 25 shifting the combs endwise alternately in opposite directions.

As a yielding means for acting upon the combs to draw them together, I employ a long spring or elastic member 25, which is 30 attached to the end combs by being passed through a perforation 26, in the back of the first comb and knotted on the end and similarly passed through a hole 27, in the last comb and knotted. The intermediate combs 35 are formed with holes 28, 29, and 30, respectively, for the passage of the spring or elastic 25, and it will be noted that these holes are not in the same relative location in each comb but it varies so that when the 40 combs are spread out or expanded and likewise when they are closed on each other the holes bear a staggered relation, as indicated more particularly in Figs. 1, and 2, also Fig. 4. As the elastic 25 passes loosely through 45 the holes in the intermediate combs, the staggered arrangement of the holes causes the elastic to act in a way that tends to shift the combs alternately in opposite directions, that is to say, the stretch of elastic between 50 non-adjacent combs will act to shift the comb between to one side in the effort of the elastic to straighten itself. Accordingly the set of combs are automatically moved in the proper directions, both as to the sidewise 55 and endwise movements, and the alternate shifting of the combs is controlled when the links are alternately bent or set as above stated. The links or blades which may be of flexible steel or of tin or wire construction, may be attached in any suitable well known manner to the combs in such manner that each individual comb can be pushed either to the right or to the left or only one way alternating. The said flexible links

permit the structure to be flexed as a whole 65 and to thereby move the combs out of the common plane or the normal planes of the respective combs, in applying the apparatus. For instance, if the combs are merely attached to each other by means of the links, 70 they are movable in both directions, but by the provision of the spring or elastic stretched from the first to the last comb and passing through holes in the intermediate 75 combs or between the teeth of the same, in the manner hereinabove described, the individual performing the work is assisted and guided and the combs shifted as desired.

The links or blades pivoted between the combs are so made that they may be varied 80 in length by changing their points of attachment at either or both ends of the respective links. To accomplish this I provided each link with a series of holes 31, 31, at each end thereof so that by removing the pin or screw by which the link is pivoted to the back of the comb, the link may be disconnected and the pivot re-set in another hole to shorten or lengthen the link as the case may be. Thus the waves produced are 90 not limited in size but may be varied and the size predetermined by the adjustment of the links before starting the process. The elastic connection may be shortened or lengthened as desired in order to secure the 95 desired tension.

In the modification shown in Fig. 8, instead of a single spring 25 being used, I employ individual springs 32, connected between adjacent combs diagonally though 100 they might be straight, as the folding of the links will effect the desired endwise shifting of the combs alternately, as shown in Figs. 3 and 5. The springs indicated are spiral metal ones though they may be rubber cord like that shown at 25.

While in the form of apparatus herewith shown, there is a set of combs connected by pivoted links and springs or elastic means combined therewith, it will of course be understood that such spring or elastic means may be dispensed with and my improved apparatus used without the same, as herein pointed out.

The length of the combs is only limited 115 by the curves of the head, but I prefer them shorter than the circumference of the head, that is to say of a length to cover the whole circumference in from four to six sections. The teeth of the individual combs being 120 incut or arched, fit the average contours or elevations of the human head and the individual teeth can also be made telescopic so that pressure on the comb or device will shorten the teeth over the elevations of the head and 125 produce a gripping effect of all the teeth on any shape of head and the hair it is desired to wave.

From the foregoing description of the apparatus its operation will be readily understood. The hair is first combed, either wet or dry, into a straight direction, then the 5 combs are spread out or extended so as to fall substantially in line with each other, as shown in Figs. 1, and 2, and are then placed over the straight-combed hair beginning nearest the face or forehead and the teeth of 10 the combs are fully inserted in the hair after it has been wetted. Then the second comb is moved forward toward the first and front one and in such sidewise movement is carried endwise to one side and then the third 15 comb is moved forward toward the second one at the same time being shifted endwise in the opposite direction to the second, and this operation is repeated with the remaining combs until each one of the set has been 20 properly positioned. A few ordinary hairpins are then inserted temporarily in the hair between the adjusted combs to retain the hair in its waved position while the combs are being removed and the hair is then dried. 25 The temporary use of hair-pins may of course be omitted. The compound movement of the comb draws the hair along with it and the resultant action produces the waves 34, in the hair 35, as shown somewhat 30 diagrammatically in Figs. 5, and 6, the hair being drawn forwardly and sidewise at the same time. In some cases where the set of combs when contracted for say half of the space occupied by the combs when extended, 35 the hair is drawn into a space about half the length of that covered by the straight-combed hair at the beginning of the operation. The links being pivoted to the backs of the combs do not interfere with the hair 40 and while it is preferable to use two links between adjacent combs, one link may be employed if desired and the same attached above and between the teeth as shown with the two links.

45 My improved hair waving device is especially adapted for waving natural hair on the head, though it may be used for waving other hair, as hereinbefore pointed out.

I wish to be understood as not limiting my 50 invention to the particular constructions herewith shown, as it is manifest that various changes may be made in the several different parts of the apparatus, without, however, departing from the spirit of my invention.

Having thus described my invention, what I claim and desire to secure by Letters Patent is:

60 1. A hair waving apparatus comprising a plurality of hair-engaging devices, jointed means operatively connected with said devices and said connecting means being constructed and arranged to permit the placing of said hair-engaging devices in the hair in laterally spaced apart relation and said con-

necting means being operable to permit said devices to be individually moved endwise.

2. A hair waving apparatus comprising two or more hair-engaging devices, jointed means operatively connected with said devices and constructed and arranged to permit the placing of said hair-engaging devices in the hair in laterally spaced apart relation and said connecting means being operable to permit said devices to be independently moved endwise alternately in opposite directions. 70

3. A hair waving apparatus comprising a plurality of hair engaging devices having means connecting them together and arranged to be placed in the hair in spaced apart sidewise relation and to be moved relatively endwise and toward each other. 80

4. A hair waving apparatus comprising a plurality of hair engaging devices, means connecting said devices together, said connecting means being constructed and arranged to permit the placing of said devices in position in the hair in a spaced apart sidewise relation and to permit said devices 90 to be individually moved endwise, and means tending to move said devices alternately endwise in opposite directions and to retain said devices in the shifted positions. 95

5. A hair waving apparatus comprising a plurality of connected hair engaging devices arranged and constructed to be placed in the hair in spaced apart sidewise relation, and means acting to draw the hair engaging devices laterally toward each other and to move them relatively endwise. 100

6. A hair waving apparatus comprising two or more hair-engaging devices having means connecting them together and constructed and arranged to be placed in the hair in spaced apart sidewise relation and to be moved to bring the devices closer together sidewise and into relatively endwise shifted positions. 105

7. A hair waving apparatus comprising a plurality of hair engaging devices disposed in substantially sidewise relation to each other, means acting to draw the said devices toward each other, and means serving to move the said devices endwise alternately in opposite directions. 115

8. A hair waving apparatus comprising a plurality of hair engaging devices constructed and arranged to be placed in the hair in spaced apart sidewise relation, pivoted links connected between adjacent hair engaging devices, and resilient or elastic means secured to the respective end hair engaging devices and engaging the intermediate devices. 120

9. A hair waving apparatus comprising a plurality of hair engaging devices and means acting to draw the said devices toward each other, said means engaging ad- 130

- 4
18. A hair waving apparatus comprising two or more hair-engaging devices movably connected together in laterally disposed relation, said devices being individually constructed to longitudinally conform in the plane of the device substantially to the shape of the head of the subject, the said connecting means of the devices providing also for the conformation of said devices as a set substantially to the curved surface of the head. 60
19. A hair waving apparatus comprising two or more hair-engaging devices arranged side by side and having means connecting them movably together, said connecting means providing for the flexing or movement of the said set of devices out of a common plane to accommodate the set to the shape of the head of the subject. 70
20. A hair waving apparatus comprising two or more combs connected movably together in laterally spaced apart relation, 80 the ends of the teeth of each comb being disposed on an upwardly curved line to longitudinally conform substantially to the shape of the head of the subject, the combs being relatively movable. 85
21. A hair waving apparatus comprising two or more hair-engaging devices arranged in laterally disposed relation and provided with pivoted links connecting them together, the said links serving as connecting and guiding means for said devices and as a supporting frame therefor. 90
22. A hair waving apparatus comprising a set of hair engaging devices 1, 1, arranged side by side and provided with links, such as 7 and 8, pivoted between adjacent devices. 95
23. A hair waving apparatus comprising a plurality of hair engaging devices, means connecting said devices together, said connecting means being constructed and arranged to permit the placing of said devices in position in the hair in a spaced apart sidewise relation and to permit said devices to be moved independently, and means tending to move said devices alternately in a staggered relation and to retain said devices in the staggered relation thereby obtained. 100
